Term of patent 3½ years

To all whom it may concern:

Be it known that I, Julia Richards, citizen of the United States, residing at 1346—63rd St., Brooklyn, in the county of Kings and State of New York, have invented a new, original, and ornamental Design for a Dress Ensemble, of which the following is a specification, reference being had to the accompanying drawing, forming part thereof.

Figure 1 is a front view of a dress ensemble, showing my new design;

Figure 2 is a front view of the dress member of the ensemble shown in Figure 1;

Figure 3 is a rear view of Figure 2, and

Figure 4 is a rear view of the jacket member of the ensemble shown in Figure 1.

The characteristic feature of my design resides in the combination on the ensemble disclosed of the specific jacket member, which has a curved front opening, curved cuffs and embroidery on one of the breast pockets, in association with the specific shirt waist dress, all as shown.

I claim:

The ornamental design for a dress ensemble, substantially as shown and described.
